UNITED STATES PATENT OFFICE

TOLBERT K. TIFFANY, OF TRENTON, NEW JERSEY, ASSIGNOR TO JAMES H. BELL, OF PHILADELPHIA, PENNSYLVANIA

INCUBATOR

Application filed May 20, 1925. Serial No. 31,510.

This invention relates to incubators, and it is more particularly directed toward providing reliable and efficient air circulation and heating so that the exacting conditions of temperature and ventilation necessary to the process of incubation through its various recognized phases or periods may be properly maintained and successful hatching thereby pre-assured.

10 One way in which this desideratum may be attained will be readily apparent from the detailed description hereinafter of a typical embodiment of my invention, the appended claims serving to define those features which I believe to be novel and therefore patentable.

With reference to the drawings, Fig. I is a front elevation of an incubator organization conveniently embodying my improvements.

Fig. II is a longitudinal sectional view of the incubator.

Fig. III is an end elevation of the same, viewed from the right of Figs. I and II.

25 Fig. IV is a cross sectional view, taken as indicated by the arrows IV-IV in Fig. II.

Fig. V is a central cross sectional view of the structure, taken as indicated by the arrows V-V in Fig. II.

Fig. VI is a detail sectional view showing a modification of which my invention is capable; and,

Fig. VII is a partial longitudinal sectional view of still another modification.

In these illustrations, the housing of the organization is comprehensively indicated at 10, and shown as divided by a central longitudinal partition 11 into two incubator sections 12, 12 which are exact counterparts of one another, both as to construction and appointments. Each section 12 affords an elongated incubating chamber 13 capable of accommodating, side by side, two rack structures 14 for supporting egg trays 15 preferably in superposed relation as shown. Per se, these egg racks constitute the subject matter of a separate application No. 31,511 filed by me simultaneously herewith which has matured into Patent No. 1,722,973, dated

July 30, 1929, and need not therefore be referred to herein except in a general way. The bottom 16 of each incubating chamber 13 is elevated above the ground or floor level, the space 17 beneath being coextensive with the corresponding section 12 and entirely enclosed, as shown, for better thermo-insulation at this region. The end walls 18 of the incubator sections 12, 12 are likewise made hollow, as shown in Fig. II, and serve as passages via which fresh air is conducted to the chamber 13, as will be presently explained. In order to permit ready access to the tray racks 14 individually, each of the incubator sections 12 is equipped with two sets of doors, each such set comprising an inner pair 19, 19 which are glazed as illustrated at the left side of Fig. I, and an outer pair 20, 20 which are opaque and shown closed at the right side of the figure just referred to. The opaque doors 20 are used to keep the incubating chambers dark during certain stages or periods of incubation; while the glazed doors 19 permit observation of the eggs from time to time without necessitating their exposure to outside atmosphere.

Fresh air enters the incubator sections 12 through gratings 21 that protect the inlet ends of conduits 22 in the base 17 extending directly beneath the hollow end walls 18 and communicating with the latter by way of a series of apertures 23, see Fig. IV. These apertures 23 are graduated with regard to diameter so as to insure even distribution of the air flow into the hollow end walls and at the same time offset the possibility of short circuiting. Referring to Fig. II, it will be observed that the end walls 18 of each section 12 are subdivided by intermediate partitions 24 into up-flow branches 25, and down-flow branches 26, the two branches communicating in each instance at the top through an opening 27, and the branch 26 directly with the incubating chamber 13 at the bottom through an opening 28. The up-flow branch 25 of each air passage contains heating means in the form of coil banks 29 whose heat-radiating elements or convolutions are arranged

vertically and staggered to define an undulatory course for the air, as shown by the arrows. As a consequence of this arrangement of what may be conveniently termed a "return flow" or reversed-directional inlet passage, the air is obliged to contact intimately with the pipe convolutions and is thereby uniformly and quickly heated previous to entering the incubating chambers 13.

The air leaves each incubating chamber 13 via a centrally located flue 30, the upper portion 31 whereof is in the form of a vertical pipe that extends through the top of the casing 1, while the lower portion 32 is expanded or broadened to the full width of the chamber 13, the side walls of said portion terminating short of the floor to provide the communicating openings 33. Within the enlarged portion 32 of the flue 30 is placed an auxiliary bank of heating coils 34, which by virtue of its position, promotes upward draft in the pipe 31 and thereby induces circulation of the air without in the corresponding incubator section 12.

In order that the circulation through the incubator sections 12 may be properly governed, I provide for exhaust of air from each of the air flow passages in the hollow end walls 18 by way of outlets 35 extending through the roof of the enclosure, the dampers 36 for these outlets being hung to the ends of levers 37 subject to thermostats 38 located within the incubating chambers 13. If desired, such exhaust openings may be located in the front wall of the housing 10 at a point about midway of the height of the latter, as shown at 35a in Fig. VI and at 35b in Fig. VII. In the former case I make use of a flapper valve 35c coordinated with a thermostat 38 in an obvious manner needing no detailed explanation herein; whereas in the latter instance, the opening 35b leads from a by-pass 39 set apart in the down-flow air passage 26 by partitioning 40, efflux through the by-pass being controlled by a damper 41 subject to a thermostat 38d as aforesaid within the incubating chamber 13. By employing the by-pass 39 just described, to protect an exhaust outlet 35b located in a side wall of the incubator, it is possible to avoid back draft.

As a further precaution against overheating I may employ additional exhaust openings 43 (Fig. II) for escape of air direct from the incubating chambers 13, these openings being preferably located centrally above the tray racks 14, and their dampers 44 respectively hung from the levers 37, of the thermostats 38 so as to be actuated simultaneously with the dampers 36 of the outlets 35.

Hot water which I preferably use as the heating medium, is supplied from a heater 45 which is common to both incubator sections 12. The flow pipe 46 of the distribut-

ing system rises from one side of the heater 45 to the level of a header pipe 47 which is, in turn, connected to a pair of mains 48 extending in parallel across the top of the housing 10. To these mains 48 are respectively connected the upper terminals 49 of the main coil banks 29, in the end walls 18 of each incubator section, as well as the upper terminals 50 of the auxiliary coil banks 34 in the respective flues 30. The return pipe 51 leading to the opposite side of the heater 45 is likewise connected to a transverse pipe 52 which is common to mains 53 extending longitudinally through the hollow base 17 of the structure and affording connection for the lower terminals 54 and 55 of the coils 29 and 34, respectively. By thus connecting the coil banks 29, 34 of each incubator section 12 in parallel with the flow and return mains 48, 53 each of said coils receives its proper apportionment of the flow of heating medium. In order that the flow in the several coil banks 29, 34 may be individually controlled, a valve 56 is provided for each of them at its juncture with the supply main 48, at the top of the housing 10. As a means to enable a portion of the flow of heating medium to be diverted from the coil banks 29 and 34 for general control of the system, I employ a by-pass pipe 57 that extends vertically between headers 58, 59 respectively connecting the outer ends of the supply and return mains 37 and 53 exteriorly of the housing 10. The by-pass pipe 57 has a valve 60 interposed in it which will enable regulation of the quantity of the heating medium diverted, so that the desired working balance may be established and maintained in the system.

In operation, the fresh air entering the incubator through the inlets 21 finds its way to the up-flow branches 25 of the passages in the end walls 18 of the respective incubator section 12. In moving upward through the branches 25 the air, in encountering the staggered convolutions of the coil bank 29 is caused to follow a zig-zag or undulatory course and is thus quickly and uniformly heated by intimate contact with the pipes. From the up-flow branch 25 in each instance, the heated air passes through the opening 27, over the top of the partition 24 and into the adjacent down-flow branch 26, descending in the latter and finally entering the incubating chamber 13 at the bottom through the opening 28. The two air streams thus entering the incubating chamber 13 from opposite ends, first rise and then take generally horizontal courses in opposite directions through the racks 14 respectively, and about the eggs on the trays 15. However, before making their exit, these two opposed air streams are obliged to descend again to the bottom of the chamber 13 for passage through the openings 33,

into the flue 30 which leads to the exterior, as already explained. By virtue of the draft artificially induced in the flue 30 by the auxiliary coil banks 34, a constant circulation of air is assured, such circulation being automatically regulated by escape through the openings 35 and 43 under governance of the thermostats 38. Thus, for example, when the temperature within the chamber 10 has a tendency to increase by reason of the added animal heat given off by the eggs during the later phases of the incubating period, the thermostats 38 will so automatically govern escape through the openings 35 and 43 as to effect moderation in the air flow and a corresponding compensative balance in the heat artificially supplied. When required, the individual valves 56 of the main coil banks 29 may be adjusted so 20 that different conditions of temperature may be maintained in the two separate incubator sections 12. On the other hand, general modification of the flow of the heating medium in the whole system may be effected by 25 varying the amount diverted through the by-pass pipe 57 as a result of adjustment of the valve 60 interposed therein.

Having thus described my invention, I claim:

30 1. In an incubator, the combination of an incubating chamber, an up-and-down passage via which air enters said chamber at the bottom and in the up-portion only whereof it is heated, a by-pass set apart in 35 the down-flow portion of said passage connecting with the exterior of the incubator to permit escape by way of the by-pass of heated air from said passage, and thermostatic means automatically controlling such escape 40 in accordance with temperature conditions prevailing in the incubating chamber.

2. In an incubator, the combination of an incubating chamber, a vertically up-and-down passage through which air flows en- 45 route to and enters the incubating chamber at its bottom and in the up-portion only whereof it is uniformly heated, an outlet by-pass set apart in the down-flow portion of the passage permitting escape of heated 50 air at a point about midway of the down passage, and thermostatic means for automatically controlling diversion of the flow of heated air by way of the by-pass in accordance with the temperature conditions pre- 55 vailing in the incubating chamber.

3. In an incubator, the combination of an incubating chamber, a vertical passage via which air enters the incubating chamber, said passage having an up-flow entrant 60 branch containing heating means, and a down-flow exit branch, a by-pass extending downwardly to an intermediate point in said exit branch permitting escape of heated air to the exterior, and thermostatic means 65 automatically controlling efflux through the

outlet in accordance with temperature conditions prevailing in the incubating chamber.

4. In an incubator, the combination of an incubating chamber, an up-and-down passage with heating means in the up portion only via which air enters the chamber at its bottom, independent air discharge outlets respectively from a point intermediate the ends of the aforesaid passage and from the incubating chamber, and co-ordinated thermostatic means for simultaneously governing efflux through said discharge outlets to automatically regulate inflow through the incubator.

In testimony whereof, I have hereunto signed my name at Trenton, New Jersey, this fourteenth day of May, A. D., 1925.

TOLBERT K. TIFFANY.
